UNITED STATES PATENT OFFICE.

GUSTAV M. VIERNOW, OF ST. LOUIS, MISSOURI.

STONE-SAWING MACHINE.

SPECIFICATION forming part of Letters Patent No. 372,996, dated November 8, 1887.

Application filed May 7, 1887. Serial No. 237,447. (No model.)

To all whom it may concern:

Be it known that I, GUSTAV M. VIERNOW, of the city of St. Louis, in the State of Missouri, have invented a certain new and useful Improvement in Stone-Sawing Machines, of which the following is a full, clear, and exact description, reference being had to the accompanying drawings, forming part of this specification, and in which—

Figure I is a plan or top view of my machine, showing the arrangement of the gang-saws in their guide-frames, the transverse shaft to which they are secured, and the pitman-rods that connect the gang with the eccentric crank-wheel that operates them. Fig. II is a detail side elevation, showing movement of the pitman-rod, its means of attachment to the saw and to the eccentric crank-wheel that operates it, with the spring friction-belt that runs the wheel. It also shows the means of vertical adjustment of the saw as it follows up its work. Fig. III is a detail showing the means of attaching the saw on the rod that connects the gang. Fig. IV is a vertical section on line IV IV, Fig. V, showing the saw with its vertical arms for steadyng it in the guide-frame and distributing the cutting-sand along the saw-cut in the stone. Fig. V is a vertical section showing the guide-frame elevated on its pedestals and the position of the saws within the guide-plates.

My invention relates to machines for sawing stone; and the invention consists in features of novelty hereinafter fully described, and pointed out in the claims.

Referring to the drawings, in which similar figures of reference indicate like parts in all the views, 1 represents the side sills of the frame that carries the machine.

2 are the forward posts, and 3 the rear posts; 4, the main beams, and 5 the cross-beams; 6, the ties, 7 the cross-braces, and 8 the rear braces, of said frame.

9 are the crane-beams or gang-bearers, the feet of which are secured to the beams 5 and their upper ends supported on the extension 10 of the forward posts.

11 represents the saws, which are bevel-pointed on the under side at 12, and having 50 vertical arms 13, that rise from near the middle

of the saw, and are integral with the saw-plate. The saw-plates at their fast ends are secured to the arms 14 of sleeve-brackets 15, to which they are fastened by bolts 16, secured by nuts 17. The sleeves of said brackets that carry 55 the saws are adjusted on the gang-shaft 18 at distances apart to correspond with the thickness of the slabs to be cut, and the sleeves are secured to the gang-shaft by collars with set-screws 19, thus securing the saw to the gang-shaft opposite the position in the stone where the cut is to be made. I have shown four of these saws in the gang; but I do not confine myself to that or any particular number, for it is evident that the number may be increased 60 or diminished according to the thickness of the slabs and the number of cuts it is desired to make.

20 represents the pitman-rod, which, as also its brace-rod 21, are provided with clips 22 at 70 their forward end, which grasp the gang-rod that passes through them. Wedges 23, that pass through the clips back of the gang-rod, take up the slack at the connections of said pitman with the rod. The clips 24 on the 75 rear ends of the pitman engage with the wrist-pins 25 on the crank-wheels 26, the slack being taken up by wedges 27. The crank-wheels are rigidly secured to the same shaft, 28, that carries the drive-pulley 29, so that as 80 the pulley is driven by the belt 30 the crank-wheels rotate at the same speed and carry the wrist-pins, with the pitman, around with them, said pitman being thus actuated to work the shaft and the saws that it carries.

The drive-belt, which may be driven by any suitable power, has a tightener or spring-tension attachment consisting of two pairs of arms, 31, that are pivoted on the same shaft, 28, that carries the pulley and crank-wheels, said arms 90 being united by spiral springs 32, and carry idlers 33 on their outer ends, said idlers running on the pivot-rods 34, that connect the twin arms, press on the drive-belt, and thus increase its tension on the pulley.

35 represents vertical feed-screw shafts, the feet of which are seated on the side sills, from which they pass upward to and through the side beams, against which shoulders 36 engage to keep the screw from lifting.

95

100

37 represents yokes, which are provided with internal screws that engage around the feed-screw shafts and uphold the shaft 28, that carries the drive-pulley, crank-wheel, and pitman.

I will now proceed to describe my feeding movement by which the pitman-rods and the gang-saw shafts they work are lowered to their work as the saws effect their cut. The top 10 ends of the vertical feed-screw shafts 35, after passing through the beams, are provided with bevel-pinions 38, that mesh with bevel-pinions 39 on the horizontal shaft 40, that runs transverse to the frame, and has bearings at 41 on the joist-bearers 42, which pass from the rear cross-beam to the tie 43, that connects the rear ends of the side beams. The shaft 40 is also provided with a bevel-pinion, 44, rigidly secured thereto, which meshes into a bevel-pinion, 45, on the end of the actuating shaft 46, which has bearings 47 on studs 48, that are secured to the cross-beams of the frame. A hand-wheel, 49, on the said shaft operates the same, and through its bevel-pinion gearing 25 turns the vertical feed-screw shafts so as to enable the operator to lower the rear end of the pitman as the saw follows down in its saw-cut. The shaft 40 is also provided with a sprocket-wheel, 50, rigidly secured thereto, an endless chain, 51, from which engages around a pulley or sprocket-wheel, 52, that is rigidly secured to the windlass-shaft 53. Two ropes, 54, secured to the said shaft wind around it at their fast end and pass over idlers 55, that run on pins 56 in the slots 57 in the crane-beams 9, through which the ropes pass on their way to the pulleys 58, that run on pins 59, which connect the bracket-arms 60, the lower end of which engage around the saw-gang shaft 18 to 30 hold up the same. The rope, after passing around said pulley, extends upward to the end of the crane-beam, to which it is fastened by the staple 61.

It will be seen that by the above-described device when the hand-wheel 49 is turned in the right direction it operates simultaneously both its bevel-gear connections with the vertical feed-screw to lower the rear end of the pitman, and by its combined gear and tackle 45 connections with the crane to effect the lowering of the saw-gang shaft at the same time, so that by the one operation of turning the hand-wheel the saws are lowered to its feed; also, after having made its cut by the reverse 50 action of the hand-wheel the gang is raised for effecting another cut. The gearing and tackle are so relatively arranged that both ends of the pitman are lowered and raised at the same rate.

60 62 represents the guide frame, which is set on the rock or stone 63 that is to be sawed, and consists of the angle irons 64, on which rests the spacing-timbers 65, which are secured to the angle-irons by bolts 66, the heads 67 of 65 which serve as feet to support the guide-frame slightly above the stone. Nuts 68 are secured down on said bolts tight on the spacing-tim-

ber. Two posts, 69, on each side of the guideway support elevated guide-boards 70, that are secured by bolts 71 to the head of the posts 70 and extend as far as the track of the vertical arm 13 and reaches in its movements to guide and steady said arm, and, in conjunction with the braces 72 from the posts to the angle-irons and their foot-bolts 77, steady the guide-frame. 75 Upper spacer-strips, 73, are bolted at the heads of the posts parallel with the bottom spacers, 65.

When it is required to saw either thicker or thinner slabs, the spacing-timbers are unbolted 80 and removed and other spacers of the requisite length to correspond with the required thickness of the slab are bolted on in their place.

74 represents an extension at one end of the shaft 40, outside the bevel-pinion 39, on which 85 is rigidly secured the pulley 75, on which a drive-belt, 76, engages. This belt connects with and is driven by the same power that works the gang-saws, and is used, after the saws have cut through, to elevate the gang 90 ready for a fresh cut. It is evident that said shaft, if turned by power, as described above, and in the right direction, will elevate the gangs in the same manner as if turned by the hand-shaft 46.

Although it would be needless to apply other than hand-power in lowering the feed at short movements, it is a great saving of labor to elevate for a recut by the same power that works the gangs.

95 The machine is intended especially for use in cutting from the solid rock in the quarry, where saws operated from both ends could not work; but it is also adapted for sawing blocks when required. The vertical arm extending 100 up from the middle of the saw acts as a distributor when sharp cutting-sand is fed into the cut for hastening the action of the saw on the stone. It also, as it works between the elevated bars of the guideway, steadies the 105 movement of the saw, and, by adding weight to the same, hastens the cut. The windlass-shaft 53 has bearings in the journal-boxes 78, which, with their caps 79, are securely fastened to the feet of the crane-beams by the bolts 110 80. The sleeve-brackets 15, that couple the saws to the gang shaft, have a loose vertical bearing, which is found necessary for the successful working of the saws to allow them a 115 lively action and free vertical movement and 120 following in their cut, but are rigidly restrained by the collars and set-screws 19 from endwise movement on said shaft.

125 Some of the advantages of my stone-sawing machine may be stated as follows: First, the combined tackle and geared system of feeding as the saw advances in its cut, in conjunction with the reverse feed for elevating the gang, is a ready means by which to operate the same; second, the means of driving the gang-saws 130 by the drive-pulley, in conjunction with the crank-wheels operating on the same shaft and the spring-tension for enforcing the friction of the drive-band; third, the gang-shaft on

which are adjusted the saws and their means of loose vertical adjustment by their sleeve-brackets, which are rigidly laterally confined from endwise movement on the gang-shaft by the collars and set screws that hold them; and, fourth, a considerable advantage is experienced from the overhung bevel edge of the saw-points, by their riding over the hard particles embedded in rocks, where a square or underhung point would be imperatively held thereby, and endanger the breaking or violent straining of the saw; and, also, as the overhung bevel-point of the saw at the end of the cut strikes the short upward incline the front end of the saw is elevated and the sand and water flows along the saw-channel and distributes the sand, and at the same time the vertical arm of the saw-blade still further aids the distribution.

20 I claim as my invention—

1. In a stone-sawing machine, the combination, with the frame having mounted thereon crane-beams and a vertically-adjustable drive-pulley, of one or more saws mounted on a gang-shaft, said gang-shaft being supported from the crane-beams, a drive-shaft actuated by the pulley, and driving-connections between the saws and the drive-shaft, substantially as herein set forth.

30 2. In a stone-sawing machine, the combination of the drive-pulley 29, operated by the drive-belt 30, with the spring-tension arms 31, connected by the spiral springs 32, which, as the idlers 33, having bearings on the coupling-rods of the arms, press on the drive-belt, cause an elastic tension of the belt on the drive-pulley, substantially as described, and for the purpose set forth.

35 3. In a stone sawing machine, the combination of the drive-pulley operated by the drive-belt under spring-tension, turning the combined shaft of said pulley, and the crank-wheels that operate the pitman-rods, the screw-yokes 37, in connection with which said pitman-rods are supported at their rear ends on the feed-screws 35, and the adjustable tackle that supports the front ends of the pitman-rods with the gang-saws, the same being operated to feed the saws by the hand-wheel 49, and shaft 46 with its bevel-geared connections with the feed-screw and its gear and tackle connections with the gang, substantially as described, and for the purpose set forth.

40 4. In a stone-sawing machine, the combination of the drive-pulley and its spring-tension device on the drive-belt, the combined geared and tackle adjustable feed device, operated by the hand-wheel 49, the saws adjustably secured to the gang-shaft by the sleeve-brackets, which allow loose vertical movement on said shaft for the free movement of the saws in their cuts, and are prevented from endwise movement on said shaft by the collars and set-screws 19, substantially as described, and for

5. In a stone-sawing machine, the combination of the saws adjustably secured on the gang-shaft, said saws having vertical arms 13, rising from the middle of the blade, that pass between the angle-irons 64, and the strips 70 of the guide-frame 62, to steady the saws and distribute the sand and water in the cut, substantially as and for the purpose set forth.

6. In a stone-sawing machine, the combination of the saws adjustably secured to the gang-shaft, said saws having overhung bevel-points inclined upward and arranged, as they strike the upward incline at the end of their cut, to lift the saws from their bed and allow the sand and water to flow along the channel, substantially as described, and for the purpose set forth.

7. In a stone-sawing machine, the combination of the saws with sleeve-brackets adjustably secured and fastened by collars and set-screws on the gang-shaft, and said saws working through the tracks of the guide-frame, made with angle-irons 64 and strips 70, elevated on posts 69, with braces 72 on each side of the tracks, and having spacing-strips 65 and 73 to regulate the distance apart of the cuts and consequent thickness of the slabs to be sawed, substantially as described, and for the purpose set forth.

8. In a stone-sawing machine, the combination of the pitman-rods secured to screw-threaded yokes 37, that engage around the vertical feed-screws, said feed-screws operated by the hand-wheel 49, that turns the shaft 46, a bevel-pinion on which meshes with its corresponding bevel-pinion on the shaft 40, which has bevel-pinnions 39, that mesh with bevel-pinnions 38 on the heads of the feed-shafts, which, with the geared and tackle feed attached to and suspended from the crane-beams 9, to support the gang when operated by said hand-wheel, feed the saws to their work, substantially as and for the purpose set forth.

9. In a stone-sawing machine, the combination of the feeding device consisting of the vertical screw-shafts, on which are engaged the screw-threaded yokes that support the rear of the pitman-rods, the bevel-pinion connections of said shafts via the shafts 40 and 46, with the hand-wheel 49 and the gear and tackle feed-connection from said shaft 40, via the sprocket-wheels 50, endless chain 51, pulley 52, ropes 54, and crane-beam 9, with its idlers 56 and gang-pulleys 58 to support the gang, all operated by said hand-wheel to feed the gang to its work, with the extension 74 of shaft 40, and drive-pulley 75, on which the drive-belt 76 engages, after the saws have effected their cut, for the return elevation of the gang, ready for a renewed cut, substantially as and for the purpose set forth.

GUSTAV M. VIERNOW.
